F. T. STUART

HINGE FOR BAG FRAMES

Filed Dec. 8, 1925

Patented July 19, 1927.

1,636,019

UNITED STATES PATENT OFFICE.

FRANK T. STUART, OF MAPLEWOOD, NEW JERSEY, ASSIGNOR TO THE R. NEUMANN HARDWARE CO., A CORPORATION OF NEW JERSEY.

HINGE FOR BAG FRAMES.

Application filed December 8, 1925. Serial No. 73,985.

The present invention relates, generally, to improvements in hinges; and, the invention has reference, more particularly, to that class of hinges which are used for operatively connecting the two frame-sections of a bag-frame, with a view of providing a novel and simply constructed three-part hinge, which is readily applied to the bag-frame, and is of such arrangement and construction of parts, so that the two frame-members or sections of the bag-frame are retained in their opened relation, but still permits of the closing of the frame-sections.

The present invention, therefore, has for its principal object the production of a novel and simply constructed bag-frame hinge in which the parts have been reduced to a minimum, which is readily secured in its operative position to the frame-sections, and operates to hold the frame-sections in their opened relation, but at the same time permits the opened bag-frame sections to be easily and quickly closed without any further manipulation on the part of the operator.

Other objects of this invention not at this time more particularly enumerated will be clearly understood from the following detailed description of the present invention.

With the various objects of the present invention in view, the said invention consists, primarily, in the novel bag-frame and hinge-connection therefor, and hereinafter set forth; and, the invention consists, furthermore, in the details of the construction of the parts of the said bag-frame and its hinge-connection more fully described in the following specification, and then finally embodied in the clauses of the claims which are appended to and which form an essential part of this specification.

The invention is clearly illustrated in the accompanying drawings, in which:—

Figure 1 is an elevation of one of the hinge-connections of a bag-frame, looking toward the inner face-portions of the frame-sections, the latter and the parts of the hinge connected therewith being represented in their closed relation; and Figure 2 is a similar view of the parts shown in said Figure 1, the frame-sections and members of the hinge being represented in their opened relation.

Figure 3 is a top or plan view of the parts represented in said Figure 2; and Figure 4 is a longitudinal vertical section of the same,

said section being taken on line 4—4 in said Figure 3.

Figure 5 is a collective view, showing in perspective the two pivot-plates or members of the hinge; and Figure 6 is a similar view 60 of a cam-shaped stay-member of the hinge.

Similar characters of reference are employed in the above described views, to indicate corresponding parts.

Referring now to the several figures of 65 the drawings, the reference-characters 1 and 2 indicate the leg-portions forming the ends of the usual frame-sections of a bag-frame, to be operatively connected, as in the present case, by means of hinges 3 made according 70 to and embodying the principles of the present invention, it being understood that with each bag-frame two of such hinges are used.

As shown in the several figures of the drawings, each hinge consists of two hinge-plates 4 and 5, the plate 4 being formed at one of its end-portions with angularly bent extensions 6 and 7, having a space 8 between them, and the extension 7 which is of greater length than the extension 6 being 80 provided at its free end with a pintle-receiving eye, as 9. The said hinge-plate 4 is also provided with perforations 10 for the reception of rivets 11, or the like, for securing the same in its operative position, in the manner shown, to the leg-portion 1. In a similar manner, the hinge-plate 5 is formed at one of its end-portions with angularly bent extensions 12 and 13, having a space 14 between them, and the extension 13 which is 90 of greater length than the extension 12 being provided at its free end with a pintle-receiving eye, as 15. The said hinge-plate 5 is also provided with perforations 16 for the reception of rivets 17, or the like, for securing the same in its operative position, in the manner shown, to the leg-portion 2. The reference character 18 indicates a suitably shaped stay-member from the main body-portion of which extend a set of fingers or 100 horns 19 and 20, having a space 21 between them of a width substantially equal to the thickness of the hinge-plate 5. The body-portion of said stay-member is also provided with a pintle-receiving perforation 22, and with a marginal projection 23, forming with the finger or horn 20 a marginal depression, as 24.

In their assembled relation, the space 21 between the fingers or horns 19 and 20 is 110

brought into alignment with the space 14 between the extensions 12 and 13 of the hinge-plate 5, the said fingers or horns 19 and 20 being forced into frictional engagement, respectively, with the upper and lower face- 5 portions of the angular portion of the said hinge-plate 5, as indicated in Figure 4 of the drawings, the pintle-receiving eye 15 being brought into lateral alignment with the perforation 22. Next, the space 8 between the extensions 6 and 7 of the hinge-plate 4 is arranged over the edge-portion 25 of the body-portion of the stay-member, until the pintle-receiving eye 9 is brought into lateral alignment with the perforation 22, the pintle-receiving eyes 15 and 9 thus being located on opposite sides of the body-portion of the stay-member, as will be evident. The various parts are then pivotally connected by 10 means of a pintle 26. The completed hinge, thus provided, is next secured to the leg-portion 2 by means of the rivets 17, and to the leg-portion 1 by means of the rivets 11, a flat spring-plate 27, suitably perforated, 15 being first placed between the hinge-plate 4 and the leg-portion 1, and simultaneously secured in position with said hinge-plate 4 by means of the said rivets 11. As shown, the said spring-plate 27 has a portion extending 20 beyond the end of the leg-portion 1, said projecting portion being suitably bent or curved, as at 28 and 29, adapted to be brought into retaining or holding engagement, respectively, with the marginal surface-portions of 25 the projection 23 and the depression 24 when the parts are in their opened-out positions represented in Figures 2, 3 and 4 of the drawings.

The slideable arrangement of the bent or 30 curved portions 28 and 29 of the spring-plate 27 with said projection 23 and depression 24 will be fully understood from an inspection of said Figures 2 and 4 of the drawings, and it will be evident that when the bag 35 frame-sections are opened they will be fully and positively retained in their opened relations against accidental closing.

It will also be evident from the arrangement and construction of the parts that after 40 the frame-sections have been opened they can be readily closed without the least danger of destroying the operativeness and usefulness of the hinged connections.

From the foregoing description of the present invention, it will be clearly evident that 45 a neat and simply constructed bag-frame hinge has been produced, the hinged connections of which form are readily secured to

the respective frame-sections, so that a much stronger, and at the same time a cheaper construction is the result; and, furthermore, a better and much more neatly finished hinged connection is produced.

I am aware that some changes may be made in the arrangements and combinations 50 of the various parts without departing from the scope of my present invention as set forth in the foregoing description, and as defined in the clauses of the claims, which are appended to the said specification. Hence, I do not limit my present invention to the exact arrangements and combinations of the various parts as described in the foregoing specification, nor do I confine myself to the exact details of the construction of the said 55 parts as illustrated in the accompanying drawings.

I claim:—

1. A hinge for the frame-sections of a bag-frame, comprising a pair of hinge-plates, fingers extending from an end-portion of each hinge-plate, one of the fingers of each hinge-plate being of greater length than its adjacent finger, said longer fingers being 60 provided with pintle-receiving eyes, and each pair of fingers having a space between them, a stay-member having portions arranged in said spaces, said stay-member being provided with a perforation, and a pintle arranged in the eyes of the fingers of the 65 respective hinge-plates and in the perforation of said stay-member.

2. A hinge for the frame-sections of a bag-frame, comprising a pair of hinge-plates, fingers extending from an end-portion of each hinge-plate, one of the fingers of each hinge-plate being of greater length than its adjacent finger, said longer fingers being 70 provided with pintle-receiving eyes, and each pair of fingers having a space between them, a stay-member having portions arranged in said spaces, said stay-member being provided with a perforation, and a pintle arranged in the eyes of the fingers of the 75 respective hinge-plates and in the perforation of said stay-member, said stay-member having a marginal projection and a marginal depression, associated with a spring-plate having 80 portions adapted to be moved into and out of sliding engagement with said projection 85 and depression.

In testimony, that I claim the invention set forth above I have hereunto set my hand this 4th day of December, 1925.

FRANK T. STUART.
